UNITED STATES PATENT OFFICE.

ARTHUR MANTHEI, OF KEWASKUM, WISCONSIN, ASSIGNOR TO KEWASKUM
ALUMINUM COMPANY, OF KEWASKUM, WISCONSIN.

BUFFING MACHINE.

Application filed April 18, 1920. Serial No. 374,969.

To all whom it may concern:

Be it known that I, ARTHUR MANTHEI, a citizen of the United States, and resident of Kewaskum, in the county of Washington and State of Wisconsin, have invented certain new and useful Improvements in Buffing Machines; and I do hereby declare that the following is a full, clear, and exact description thereof.

10 My invention relates to new and useful improvements in buffing and polishing machines, particularly those which are adapted for use in preparing various kinds of receptacles for market.

15 The principal purpose of the invention is to provide a buffing and polishing machine which is capable of practically universal application. In other words, my primary object is to produce a machine for holding an 20 article while being polished which can be moved in a variety of directions with respect to the buffing wheel.

With this general object in view the invention consists of the novel features of construction, combination and arrangement of 25 parts which will be hereinafter more particularly described and claimed.

In the accompanying drawings:

Figure 1 represents a front elevational 30 view of a machine constructed in accordance with the invention.

Figure 2 is a longitudinal vertical sectional view through the upper portion of the machine.

35 Figure 3 is a side elevational view of the parts shown in Figure 1, and

Figure 4 is a detail section on the plane of the line 4—4 of Figure 2.

Referring more particularly to the drawings, it will be seen that my improved machine includes a support 1 formed on a base 2, a stationary standard 3 and pivoted frame 4. The frame 4 is connected to the base 2 by means of a pivot shaft 5 extending 45 through the lower ends of the former, and bearing ears 6 extending from the latter. The work carrying parts of the machine are mounted upon the upper end of this pivoted frame 4.

50 This frame 4 is held in various positions with respect to the vertical plane of the pivot shaft 5 by means of a screw shaft 7, one end of which is threaded in a pivoted nut 8 carried by the upper end of the standard 3, the other end being journalled in a pivoted

bearing 9 in the upper end of said frame. The front end of the shaft 7 adjacent the frame 4 is provided with a hand wheel 10 whereby the same can be effectively revolved so as to rock the frame and the parts 60 carried thereby as desired.

A frame table 11 is mounted on the upper end of the pivoted frame 4 and carries a cylindrical bearing head 12 on which a bracket 13 is rotatable, said bracket having a 65 socket 14 in which said head is disposed as shown in Figure 2. The preferred means for turning the bracket 13 upon the table 11 consists of a worm gear ring 15 surrounding the socket 14, and a worm 16 journalled in 70 bearings 17 on said table. A hand wheel 18 on one end of the worm shaft provides a means for readily manipulating the worm and worm gear.

The bracket 13 has a pair of upwardly 75 projecting bracket arms 19, the ends of which are spaced apart and provided with bearings 20 and 21. A sleeve 22 is slidable and non-rotatable in the bearing 21 and rotatably receives a drive shaft 23, one end 80 portion of which is slidably and rotatably mounted in the other bearing 20. The bearing sleeve 22 is retained against rotation by the arrangement shown particularly in Figure 4, from which figure it will be noticed that said sleeve has a pair of diametrically opposed slots 24 in which splines 25 extending from the wall of the bearing 21 slide.

The sleeve 22 and shaft 23 which is rotatable therein are movable longitudinally and held in different adjusted positions by means of the rotation of a feed screw 26, said screw having a nut 27 thereon which is carried by a feed collar 28, the latter being 95 locked to the said sleeve 22 as shown in Figure 2. The opposite ends of this feed screw 26 are journalled in bearings carried by the ends of the bracket arms 19 and one end thereof has a bevel gear 29 fixed thereto in 100 position to have its teeth meshed with a second bevel gear 30. The latter gear is rotated through the instrumentality of a hand wheel 31.

The drive shaft 23 is rotated by means of 105 a motor 32 disposed on a motor support 33 which is fixed to and movable with the bracket socket 14. Connection between the shaft 23 and the motor shaft is procured by a worm 34 on the latter and the worm gear 110

35 slidably splined to the former. As clearly shown in Figure 4 when the sleeve 22 and the shaft 23 are movable longitudinally, the latter is slidable through the hub of the gear 35, but operative relation is maintained in view of the spline 36.

The end of the drive shaft 23 remote from the worm gear 35 has a threaded collar 37 locked thereto and is adapted to receive a 10 suitable work carrying form (not shown). Located between this threaded collar 37 and the adjacent end of the sleeve 22 and secured to the latter to be held in nonrotative position is a hub 38 of a work holding frame 39. 15 As shown in Figure 1 this frame 39 is substantially rectangular and in the side opposite that in which the hub 38 is mounted there is disposed a second hub 40. This latter hub provides a bearing for a spindle 20 41, which is slidable therethrough, the inner end of said spindle having a work engaging clamp head 42. By means of the spindle 41 the clamp head 42 can be moved toward or away from the threaded collar 37 and when 25 its inner limit of movement is reached it is locked by the disposition of a laterally extending handle 43 in the notch of a latch plate 44.

When a machine constructed in accordance 30 with my invention is to be operated, the article to be polished is secured within the frame 39 by being disposed on the hereinbefore mentioned form which is threaded on the collar 37 and clamped thereagainst by means of the head 42. Inasmuch as the collar 37 is secured to the shaft 23 and the head 40 is rotatable, the article to be polished will be rotated within the relatively stationary frame 39 by means of the motor 32. 35 During the rotation of said article, the same and the frame 39 is readily movable outwardly away from the supporting bracket 13 by turning the hand wheel 31. A second movement of the work holding frame and 40 the article to be polished is possible by ro-

tating the hand wheel 18 which turns the entire bracket 13 and part supported thereby, as hereinbefore mentioned. By turning the other hand wheel 10 a third movement of the article to be polished and its frame 39 can 50 be procured. In other words, the pivoted frame 4 and all of the mechanism of the table 11 can be rocked upon the pivot shaft 5. Any one or all of these different movements can be obtained selectively, independently or 55 simultaneously, at the will of the operator.

From the immediate foregoing description, it will be obvious that this improved buffing and polishing machine is capable of substantially universal movement, thus rendering it applicable to many kinds of work which heretofore had to be performed on different machines with the consequent loss of time and considerable expense. Various 60 changes may be made in the different parts 65 of the invention and in its manner of use, without departing from or sacrificing any of the advantages.

I claim:

In a device of the class described, the combination of a rotary shaft, a sleeve enveloping said shaft terminating short of the ends of said shaft, a hub secured to said shaft, a rectangular frame, one side of said frame being rigid with said hub, a second hub rigid with said frame oppositely disposed and in alinement with said first mentioned hub, said second hub having an aperture therein, a stem slidable in said aperture, 70 a handle laterally projecting from said stem, 75 a latch plate having a notch for the reception of said handle, and a work engaging head on said stem inwardly disposed with respect to said second mentioned hub towards said first mentioned hub.

In testimony that I claim the foregoing I have hereunto set my hand at Kewaskum, in the county of Washington and State of Wisconsin.

ARTHUR MANTHEI.
